US00D577597S

(12) **United States Design Patent**
Snyder et al.

(10) **Patent No.:** **US D577,597 S**
(45) **Date of Patent:** **** Sep. 30, 2008**

(54) **BOTTLE**

(75) Inventors: **MarySue Snyder**, Purchase, NY (US);
Ron Pence, Purchase, NY (US);
Kenneth Hirst, New York, NY (US);
Sam Wilson, Tampa, FL (US)

(73) Assignee: **PepsiCo, Inc.**, Purchase, NY (US)

(**) Term: **14 Years**

(21) Appl. No.: **29/304,193**

(22) Filed: **Feb. 27, 2008**

D364,347 S 11/1995 Sillince et al.
D374,176 S 10/1996 Sillince et al.
D379,152 S 5/1997 Richardson
D398,539 S * 9/1998 Guislain D9/564

(Continued)

Primary Examiner—Carol Rademaker*(74) Attorney, Agent, or Firm*—Banner & Witcoff, Ltd.

(57) **CLAIM**

The ornamental design for a bottle, as shown and described.

DESCRIPTION

(62) Division of application No. 29/276,732, filed on Feb. 2, 2007, now Pat. No. Des. 568,157.

(51) **LOC (8) Cl.** **09-01**
(52) **U.S. Cl.** **D9/551**
(58) **Field of Classification Search** D9/643,
D9/649, 652, 667, 682, 687–688, 723–782,
D9/500, 503–505, 516, 529, 537–540, 546,
D9/549, 551–552, 558, 564–565; 215/382–384,
215/396, 398

See application file for complete search history.

FIG. 1 is a front left perspective view of a bottle showing a first embodiment of our new design;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof;

FIG. 8 is a front left perspective view of a bottle showing a second embodiment of our new design;

FIG. 9 is a front view thereof;

FIG. 10 is a right side view thereof;

FIG. 11 is a left side view thereof;

FIG. 12 is a rear view thereof;

FIG. 13 is a top view thereof; and,

FIG. 14 is a bottom view thereof.

The dot-dot-dash-dot-dot-dash broken lines shown in the drawings define the boundary lines of the claimed design. The dash-dash-dash-dash broken lines shown in the drawings are for environmental purposes only and form no part of the claimed design.
